(57) **CLAIM**

The ornamental design for a safety pad for angle shelf, as shown and described.

DESCRIPTION

FIG. 1 is a front side perspective view of a safety pad for angle shelf showing our new design;

FIG. 2 is a rear side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a reference view when in use thereof; and,

FIG. 10 is another reference view when in use thereof.

The broken lines in the drawings illustrate portions of the safety pad for angle shelf that form no part of the claimed design.
